INSULATOR SUPPORT FOR POWER RAILS

William C. Banks, Jersey City, N. J.

Application February 6, 1934, Serial No. 709,922

16 Claims. (Cl. 173—321)

This invention relates to electric insulators, and more specifically to insulators adapted to support running lengths of power conduits, for instance the third or power rail which supplies power to the running trains of electric railroads or subways, and the like.

A power rail spaced from the ground and supported upon such insulators at certain intervals along the rail is subject to vibrations imparted thereto from the running train. In due course the continued strain from vibrations or the like, may weaken and eventually damage the insulator. Such strain or vibrations are liable to loosen in time, certain insulator connections and eventually due to cumulative ill effects cause breakage of the insulator.

Therefore, one object of this invention is to combat such emergencies by an improved mounting or insulating support for the power rail, and which is simple, economical, and safe; another object is to strengthen certain insulator connections, and to universally raise their resistance against stresses and strains.

Another object is to provide improvements to remedy the aforementioned ill effects, which can be readily incorporated in a standard construction of insulator equipment, that is to say, without considerable changes thereof and preferably so that a change on existing equipment can be made without having to scrap essential parts of the equipment or of the manufacturing outfit.

A conventional insulating support for the purpose mentioned comprises a casting to constitute a stool or holder adapted to be firmly anchored to the tie or sleeper. Fixed to this holder is a body of insulating or non-conducting material having the necessary qualities and shape to enable it to support the power rail. The insulator body or head may be of earthenware or porcelain or other suitable materials which incidentally are mouldable during the process of their manufacture. This head is shaped substantially as a square or cubic block, which thus is adapted to have attached thereto a power rail of conventional double flanged profile fitted by its base flange for mounting in a suitable standard manner onto the flat top of the insulator. The preferred and conventional manner of attaching the power rail is through a pair of double hooked and preferably wide-lipped clamping jaws, bolted together, whereby the double hooked portions thereof engage into corresponding lateral grooves of the earthen insulator and over the base flange respectively of the power rail.

A problem in the construction of a practical insulating support of this character lies in the difficulty of combining and securely connecting with each other such different building materials as for instance the earthen or porcelain insulator on the one hand, and corresponding steel or metal elements or casting members on the other hand. The connections between these heterogeneous elements must be such as to render the structure capable not only of performing its duty as an insulator, but capable also of withstanding the attendant mechanical strain and stresses of actual service, taking into account the relative low mechanical strength and other characteristics such as brittleness of the insulating material or insulator head.

Trouble has been experienced because a weakness of the standard insulator lay in the difficulty of firmly and durably fastening the insulator to its support or holder. Particularly, a standard method of connection has not proved to be sufficiently safe, which method consists in assembling the insulator upon its foot or holder with certain clearances therebetween, and then supplying a filling material or connecting substance such as molten lead into the clearance spaces, to the end of establishing a permanent connection after the filling material has solidified. This method is, and may herein be, briefly termed as "leading" the one element into the other.

Ordinarily, an insulator support is in the form of a holder having an upright hollow open-ended casting which has a reduced vertically extending top portion in the nature of a neck preferably of non-circular cross-section. The neck is adapted to lodge, with a certain all around clearance, in a corresponding recess or socket in the bottom of the otherwise solid insulator head. When assembled and in position, the insulator head is seated upon the shoulder of the base portion of the insulator holder. The molten filling substance such as lead is poured through the hollow inside of the casting and allowed to fill in the spaces or clearances in and around the neck. The non-circular cross-section of the neck is intended to obviate in particular a possible rotary displacement of the insulator relative to the neck or stub around which it is fastened through the lead filling, and there are provided longitudinally slotted openings or elongated notches down the sides of the neck in order to permit the passage of the filling material from the inside of the neck into the outer annular clearance space.

there-around, and also to reinforce the connection after the lead has solidified in these passages as well as inside and around the neck.

This method of connection, although ingenious and still standard practice has not throughout withstood the test of time and wear, in that rotary or other displacement of the insulator head and strain of a universal character imposed thereon with subsequent destruction of the lead connection and eventually of the insulator head could not be prevented.

The invention, therefore, contemplates the provision or insertion of certain additional interlocking means between the neck portion of the insulator support or holder and the insulator supported thereby. The invention, therefore, also can be said to contemplate an arrangement for reinforcing the connection just characterized which exists between the insulator and the insulator support.

In other words, this invention aims to establish a modified and more laborious system of passages for the filling material within this connection. Such more labyrinthic passages are effective by their reinforcing and interlocking character to check the tendency of displacement of the parts under strain. To say it in still other words, a modified arrangement of the lead filling is to reduce the specific squeezing, compressing, shearing and other stresses imposed upon the lead filling or connecting substances under actual service.

According to still another aspect, this invention contemplates the suitable arrangement or insertion of certain novel interlocking means between the insulator support and its surrounding insulating head, such interlocking means preferably consisting of a suitable material of suitable shape and suitable disposition.

Consequently, one feature of the invention provides a protrusion which extends from the inner walls of the recess or socket found in the bottom of the insulator. With the parts assembled, this protrusion of the insulator head comes to lodge in a corresponding recess or the like in the insulator support or holder. It can thus be said that by the step of assembly an interlocking relationship of one kind or another is established effective preferably to check such undesirable displacements as for instance rotational displacement of the insulator heretofore experienced with standard insulator assemblies of this type.

According to another feature, the protrusion within the recess or socket of the insulator head consists of a special element anchored or fixed in the walls of the recess, preferably in such a manner that the element merges substantially undisplaceably into the material from which the insulator is made. It should be noted that this element can be positioned in the desired manner in the insulator head, while the same is being moulded or cast into its form during its process of manufacture. It is thus understood that this element or safety locking member, together with the insulator head forms a solid unit which as such can be assembled upon the insulator base portion.

According to another feature, the aforementioned protrusion is in the form of a plate or partition, which extends from side to side across the hollow or socket of the insulator head. This plate is adapted to lodge in aligned slot-like openings or elongated notches in the insulator holder.

According to another feature, an anchoring and reinforcing element is rigidly moulded with the insulator and rises from the bottom of the recess or socket, the relative arrangement of parts being such that when the insulator is assembled upon the holder this anchoring and reinforcing element will enter the hollow of the holder neck which in turn lodges in the recess of the head.

According to a still different aspect of the invention, a feature lies in the fact that the desired ends of reinforcement and security are attained by introducing into the manufacturing process of this equipment a simple inexpensive element in a certain simple manner whereby no appreciable change of standard parts need be made.

Still another feature provides for an article of manufacture which comprises the insulator head substantially as described consisting of a suitable insulating material for instance porcelain which has moulded therein or merged therewith during the process of manufacture the interlocking or reinforcing or anchoring member. Preferably that member is in the form of a plate, partition or web traversing the recess in the insulator head and firmly edgewise embedded in the walls thereof, so that the insulator head and the novel interlocking element can be considered as a manufacturing unit which as such can be brought into certain cooperative relationship with the holder during the process of assembly.

Another feature requires that one portion of a reinforcing or anchoring or connecting element is rigidly embedded in the central bottom portion of the insulator head, while another portion is also firmly connected preferably through a lead filler within the hollow of the holder. While the insulator head is thus anchored at the center, a surrounding or annular or marginal bottom portion of the insulator head is sustained upon the holder, thus offering by favorable distribution of acting forces a considerable resistance against transverse or bending stresses imposed upon the construction, thereby easing the stresses in the insulator head.

In a preferred embodiment the novel locking or interlocking or reinforcing arrangement consists of a preferably rectangular or oblong plate or web traversing lengthwise the socket opening in the insulator head whereby the plate is held in place, that is to say is chucked or closed in edgewise from three sides by the material of the insulator head. Moreover, since preferably the free end of the plate terminates within the socket, that is to say some little distance spaced from the bottom face of the insulator head it allows the surrounding material of the insulator head to close in also somewhat over the extreme ends of the fourth or exposed edge of the plate so as to make it practically indisplaceable in all directions within, and solid with, the insulator head. A safe connection or merging into each other of these two elements is thus established. The plate forms a partition or wall or web lengthwise within the socket and has a perforation through which the filling material or connecting substance such as molten lead may pass, and in which it may solidify so as to strengthen its anchorage and the intercoherence of the elements involved in this connection. It should also be noted that this plate is otherwise so arranged and dimensioned that it can readily lodge in the initially mentioned slit-like notches or cut-outs already present in standard parts of

standard equipment. Therefore, it will be noted that the plate or member 42 also serves as a positioning means in order to more correctly locate and adjust the head upon the holder. 5 Note also that the preferred embodiment of this invention can readily be incorporated without necessitating redesign of standard equipment or essential changes of parts thereof, and hence no considerable change of the manufacturing equipment.

The invention possesses other objects and features of advantage, some of which, with the foregoing, will be set forth in the following description. In the description and in the claims, 15 parts will be identified by specific names for convenience, but they are intended to be as generic in their application to similar parts as the art will permit. In the accompanying drawings there has been illustrated the best embodiment 20 of this invention known to me, but such embodiment is to be regarded as typical only of many possible embodiments, and the invention is not to be limited thereto.

Fig. 1 is a general view upon one side of the 25 rail support, showing the power rail in cross-section fastened to the insulator.

Fig. 2 is a plan view taken upon Fig. 1.

Fig. 3 is an enlarged cross-section through the insulator assembly taken upon Fig. 1 along the 30 line *a—a*.

Fig. 4 is a perspective view of the insulator head turned upside down to indicate the manner of its assembly with the insulator holder with respect to the novel interlocking means.

Fig. 5 is a part cross-section taken upon Fig. 3 35 along the line *b—b*, showing the relative position and function of the novel interlocking member.

In Fig. 1 the cross-section of a power or third 40 rail 10 discloses a profile having a base or base-flange 11, a top or contact flange 12, and a connecting web 13. The power rail is fixedly mounted upon a support or insulator collectively indicated by the number 14 which is shown to 45 be in the general appearance of an upright standard adapted to be firmly anchored upon a suitable ground base as indicated at 14a.

The insulator 13 comprises the insulator support or holder 15 and the insulator head 16 50 which latter may consist of a suitable non-conducting for instance earthen material or porcelain. The insulator head 16 is shown to have the general appearance of a block or cube having slightly tapered sides 17, a flat top face 18, and a recessed bottom portion defined by a short skirt 19, (see Fig. 3), a shallow recess 20 leading into a deeper recess or socket 21. The flat recess 20 is defined as by a conical side face 22 and an annular bottom face 23 which surrounds the socket 21, recess 20 and socket 21 being adapted to receive the insulator holder 15.

Squarely across the top face 18 of the insulator head extends a groove 24 of semi-circular cross-section shaped to receive therein a bolt 25 65 having a head 26 at one end and threaded upon the other end a nut 27. This bolt forms part of a standard clamping attachment for securing the power rail upon the insulator head, and which further comprises the two clamping jaws 28, 29 which hold the rail. The clamps are identical in shape, each of them showing the appearance of a twin hook member consisting of the oppositely directed curved or hook portions 30 and 31 and the bifurcated shank 32 consisting of two prongs 70 75 33 and 34 (see Fig. 3). When the clamping at-

attachment is in place the hook portion 31 engages in a horizontal groove 35 in the side of the insulator head while the associated hook portion 30 engages over an edge portion 35a of the base-flange 11 of the power rail (see Figs. 1 and 2). 5 The clamping bolt 25 extends between the prongs 33 and 34 of the hook members and bolt and nut hold the clamping jaws together as well as the power rail in place, which is clear from a glance at the drawings.

The insulator holder 15 is formed with a laterally extending horizontal anchoring base plate 36 having holes 37 shown to be arranged in a triangle for anchor bolts (not shown). The holder 15 is in the way of a hollow open-ended 15 steel casting which comprises a wider body portion 38 and upwardly extending therefrom a reduced stub-like top portion or neck 39, leaving an intermediate shoulder portion 40. The neck or hollow boss is shown to be preferably of oval 20 configuration (see Fig. 5) and to have relatively deep vertical notches or slots 40a cut into the side.

When assembled upon the insulator holder 15 the insulator head 16 rests or engages upon the 25 shoulder 40 of the holder while the neck portion 39 thereof lodges inside the recess or socket 21 of the insulator head. The neck is "leaded" into the recess as indicated by the lead filling 41 to 30 make a permanent connection between the insulator holder and the insulator head.

The construction so far described is that of certain standard equipment. An improvement made upon this equipment lies in the arrangement of the plate or interlocking member 42 35 and its peculiar relationship to the elements involved at this crucial point of the construction. The elements engaged in this connection are, to wit: the neck portion 39 of the insulator holder, the insulator head 16 and the lead filling 41. 40 The plate 42 is of oblong shape (see Figs. 1 and 3) and has an upper and a lower perforation or hole 43 and 44 respectively, to be permeated by the material in which this plate or interlocking member is to be embedded. In the process of 45 assembly the insulator head forms a rigid unit with the plate 42 (see Fig. 4). This will be clear from the fact that not only about half the length of the plate 42 including the perforation 43 is embedded in the material of the insulator head, 50 but that also edge portions 45 of the long sides of the plate are embedded in the walls of the recess 21 as indicated in Figs. 4 and 5. Also the fourth and exposed edge portion 46 of the plate (see Fig. 4) is allowed to merge slightly into the 55 wall of the socket at 47 since the exposed end 48 of the plate or partition terminates somewhat within the recess 21, so that in all the plate 42 is practically undisplaceably embedded in the insulator head 16. As shown in Fig. 5, the socket 60 21 has a non-circular or elliptical shape in cross-section, and the plate 42 is arranged to traverse or partition the socket-recess along the shorter axis of ellipse. In this way the plate 42 may also 65 lodge in the slots 40a present in the neck 39 of standard holders of such type, thus establishing interlocking relationship between suitable structural elements. This simple novel element will immediately relieve certain injurious stresses previously imposed upon the lead connection 70 which holds the parts together, and make the connection more positive, of greater strength, and of universally greater resistance.

In assembling and connecting the insulator holder 15 and the insulator head 16, the simple 75

procedure is as partially indicated in Fig. 4 and described as follows:

The insulator head 16 is turned upside down, the insulator holder 15 is placed into position in the recessed portion of the head so that neck 39 of the holder lodges in recess 21 of the head, and that plate 42 automatically finds its lodging in the slots 40a. Due to the non-circular or oval shape of neck 39 and correspondingly of the recess 21, the proper relative position of the parts is readily determined and established. Especially from Figs. 3, 4 and 5, it is noted that clearance spaces are provided in and around the neck 39 as well as around the plate 42 where it lodges in the notches 40a so that too close a fitting of the interlocking parts is avoided and minor manufacturing inaccuracies thereby accounted for, whereas molten lead poured through the hollow inside of the insulator holder is allowed to readily enter into and fill all clearances and spaces including the hole 44 in plate 42, thereby effectively and universally reinforcing and rendering safe the "leaded" connection between the insulator holder and the insulator head, and firmly anchoring the one upon the other.

The insulator head 16 embodying the improvement can also be considered as an article of manufacture, whereby in the course of production thereof the interlocking reinforcing member or plate 42 is firmly embedded in the insulating material of the head 16 preferably in the manner shown.

Specifically, in order to establish the lead connection, head and holder are assembled and positioned in upside down position. Lead is poured through the hollow holder 15 to fill the recess 21 in the head and the clearances and spaces around the parts therein so that eventually the anchoring or interlocking reinforcement plate 42 is firmly embedded in the material of the insulator head as well as in the lead filler.

What I claim is:

45 1. In an electric insulator construction for carrying a power conductor, the combination with a holder having a shouldered portion and a neck-like top portion rising therefrom, a head consisting of insulating material adapted to sustain the power conductor and having a recess adapted to fit substantially loosely over and around said top portion while allowing the body of the insulator head to rest upon said shoulder portion, a filler substance adapted to set in the clearances and spaces around the parts within said recess so as to make a permanent connection between said head and said holder, of reinforcing means for strengthening the connection established by said filler, respective portions of said reinforcing means are substantially embedded in said head as well as in said filler.

2. The arrangement according to claim 1, in which the reinforcing means comprise an element which pervades said head, said filler, and said neck-like top portion of the holder.

3. In an electric insulator construction for carrying a power conductor, a combination with a holder having a shouldered portion and a neck-like top portion rising therefrom, a head consisting of insulating material adapted to sustain the power conductor and having a recess adapted to have substantially freely lodged therein said top portion while allowing the body of the insulator head to rest upon said

shouldered portion, a filler substance adapted to set in the clearance and spaces around the parts in said recess to make a permanent connection between said head and said holder, of an additional structural element arranged between said head and said holder in a manner to have interlocking relationship therewith for reinforcing the connection established by said filler.

4. In an electric insulator construction for carrying a power conductor, the combination with a holder having a shouldered portion and a hollow neck-like top portion rising therefrom, a head consisting of insulating material adapted to sustain the power conductor and having a recess adapted to fit substantially loosely over and around said top portion while allowing the body of the insulator head to rest upon said shouldered portion, a filler substance adapted to set in the clearances and spaces in and around said neck-like portion to make a permanent connection between said head and said holder, of an anchoring and reinforcing element arranged to rise rigidly from the bottom of the recess and to extend into the hollow of the top portion of said holder to be embedded in said filler substance for anchorage.

5. In an electric insulator construction for carrying a power conductor, the combination with a holder having a shouldered portion and a projecting top portion rising therefrom, a head consisting of insulating material adapted to sustain the power conductor and having a recess adapted to fit substantially loosely over and around said top portion while allowing the body of the insulator head to rest upon said shouldered portion, a filler substance adapted to set in the clearances and spaces around the parts within said recess, of a protrusion rigid with the insulator head and extending from the surface of the recess therein, said protrusion and said top portion of the holder having interlocking relationship with each other when the parts are assembled.

6. In an electric insulator construction for carrying a power conductor, the combination with a holder having a shouldered portion and a projection or top portion rising therefrom, said top portion having sunk across the top thereof a relatively deep notch-like recess, a head consisting of insulating material adapted to sustain the power conductor and having a recess adapted to fit substantially freely over and around said stub while allowing the body of the insulator head to rest upon said shouldered portion, a filler substance adapted to set in the parts within said recess to make a permanent connection between said head and said holder, of a reinforcing web extending within the recess of the head and traversing from side to side thereof, said web adapted to lodge in said notch-like recess when head and holder are assembled, said web also embedded in the filler.

7. The arrangement according to claim 6, in which there is clearance between the web and the notch for the filler substance to pass therethrough.

8. In an electric insulator construction for carrying a power conductor, the combination with a hollow open-ended holder having a shouldered based portion and a substantially cylindrical hollow top portion rising therefrom, the walls of said top portion having longitudinally extending opposingly arranged slots, a head consisting of insulating material adapted to sus-

tain the power conductor and having a recess arranged to fit substantially freely over and around said top portion while allowing the body of the insulator head to rest upon said shoulder portion, a filler substance adapted to set in the clearances and spaces around the parts within the recess of the head to make a permanent connection between said head and said holder, of a reinforcing web traversing from side to side of the recess in the insulator head and rigid therewith, said web adapted to lodge in said slots when head and holder are assembled, said web also embedded in the filler substance.

9. The arrangement according to claim 8, in which there are provided means for anchoring the central portion of the web in the filler substance within the cylindrical top portion.

10. The arrangement according to claim 8, in which a substantially centrally located perforation in the web allows for passage therethrough of the filler substance thereby effective to give additional anchorage to said web.

11. As an article of manufacture, an insulator head adapted for carrying a power conductor and shaped to have in its bottom portion a recess to enable said head to be fixed upon a holder-stub with the aid of a filler medium, and anchoring and reinforcing means comprising a member rigidly extending from the inner surface of and substantially diametrically across said recess, said anchoring member embedded in the insulating material of said head and placed therein during the process of manufacture thereof.

12. As an article of manufacture, an insulator head according to claim 11, in which the anchoring and reinforcing means are endwise fully embedded in the side walls of the recess.

13. As an article of manufacture, an insulator head according to claim 11, in which the anchoring and reinforcing means comprise a plate member traversing said recess from side to side thereof.

14. As an article of manufacture, an insulator head according to claim 11, in which the anchoring means comprise a plate member traversing said recess from side to side thereof, said plate member being edgewise embedded in the sides and in the bottom of said recess.

15. As an article of manufacture, an insulator head according to claim 11, in which the anchoring means comprise a substantially rectangular plate member traversing said recess from side to side thereof and which is embedded in the bottom and in the sides of said recess, and perforations in said plate allow the respective surrounding medium to set therein so as to increase the anchoring power thereof.

16. As an article of manufacture, an insulator head according to claim 11, in which the anchoring means comprise a substantially rectangular plate member traversing said recess from side to side thereof and which is embedded in the bottom and in the sides of said recess, and means for increasing the anchoring power of said plate in the respective media in which it is embedded.

WILLIAM C. BANKS.
